UNITED STATES PATENT OFFICE.

THOMAS D. TERLIZZI, OF WORCESTER, MASSACHUSETTS.

FOLDING BUMPER FOR AUTOMOBILES.

Application filed August 27, 1923. Serial No. 659,461.

To all whom it may concern:

Be it known that I, THOMAS D. TERLIZZI, a citizen of the United States, residing at Worcester, in the county of Worcester and State of Massachusetts, have invented a new and useful Folding Bumper for Automobiles, of which the following is a specification.

This invention relates to a bumper capable of folding up when it strikes an individual, and the principal objects thereof are to provide means for permitting of its folding operation in such a manner as to avoid injury to a person struck by the bumper, and yet to provide a construction which will not expose a lot of complicated machinery to view, and will have at its ends positive fenders which will not fold on being struck, but will resist any ordinary impact to which they are subjected.

Further objects and advantages of the invention will appear hereinafter.

Reference is to be had to the accompanying drawing, in which—

Fig. 1 is a plan of a preferred embodiment of this invention shown in full lines in its normal position on the car and showing in dotted lines its completely folded up position;

Fig. 2 is a similar view showing the position of the parts when the fender strikes a person and folds;

Fig. 3 is a side elevation showing the end of the bumper;

Fig. 4 is a side view of one of these springs showing interior construction;

Fig. 5 is an enlarged sectional view on the line 5—5 of Fig. 1; and

Fig. 6 is an enlarged sectional view on the line 6—6 of Fig. 1, and

Fig. 7 is a front view.

I am aware of the fact that several devices have been invented in the nature of folding automobile bumpers. These, so far as I am aware, are of such a nature as to involve expensive and cumbersome machinery and usually of such a nature that they will look so complicated that people are not willing to put them on their cars. They also fold all the way from the end and present no surface which can resist impact without folding.

In my invention the bumper looks like an ordinary bumper and has very little mechanism aside from it that shows in any way. It is inexpensive to manufacture and install and is so arranged that it has at its two ends projecting parts of the bumper which are solid and will resist impact in the same way as an ordinary bumper made in a single piece. Yet the construction is such that if a pedestrian is struck anywhere between two points a little beyond the sides of the chassis the bumper will automatically fold with a strong spring resistance in such a way as to hold the pedestrian between two arms of the bumper and in a safe position, or else allow him to get out of the way, and at any rate strike him with yielding resistance so that he is not likely to be seriously injured.

In the drawings I have shown a bracket 10 which is mounted on the chassis in any convenient way. It is provided with a strut 11 which extends forwardly from each side of the chassis and preferably outwardly to a certain extent so as to bring its end 12 out from the side of the car a little ways. This end is curved as will be seen and it is free and not positively fastened to any other part of the device.

The bumper itself comprises two arms 14 of channel shape preferably and adapted to receive between their upper and lower flanges the ends 12 of the struts 11. Preferably the ends of these struts are fitted to the interior of the bumper arm 14 so that they will come together easily and yet not rattle, but they are not positively connected together. The end of the strut extends clear over to the inner surface of the vertical front face of the bumper arm and contacts with it so that it constitutes a strong support for it. The strut 11 is so wide that it will not yield, but on the contrary forms a positive stop against which the force of any impact on the bumper beyond the end 12 will be exerted without moving the bumper or the strut. In this way this part of the bumper 14 beyond the end 12 acts just like any bumper.

The two arms 14 of the bumper are provided with vertical pivots 15 each of which is mounted on a pivot member 16. This is

provided with a perforation 17 which is screw-threaded and receives the thread of a bolt 18. In normal position the two members 16 extend parallel with each other and longitudinally with respect to the car, so that the two bolts 18 extend away from them in opposite directions and are in alignment with each other.

The bolts 18 extend through holes in the 10 ends of a center block 20 which has a central solid portion normally located between the ends of the bumper arms 14 and of the same size and shape as these arms so as to complete the bumper at that point when it 15 is in normal position. This block has projections 21 extending outwardly and ends 22 extending forwardly provided with perforations through which the bolts 18 extend. The heads of these bolts rest on the outer 20 surfaces of these projections in all positions thereof. The pivot members 16 can swing from the position shown in full lines to that shown in dotted lines in Fig. 1, but the block 20 does not change its relative position except to move backwardly toward the car 25 when anything strikes the bumper. There are a pair of springs 23, one on each bolt 18 for resisting the motion of the pivot members 16 outwardly and forcing them to move 30 inwardly whenever possible to the positions shown in Fig. 1.

As so far described there is nothing to hold the bumper out of its operative normal position, and nothing to resist its swinging 35 back to the dotted line position in Fig. 1. For the purpose of providing this means, I have shown a projection 25 on the cast bracket 10. In this projection is a hole or perforation for receiving the end 26 of a 40 stud 27. A bolt 28 is provided for holding it in position. In this stud is fixed by means of a pin 29 a strong coiled spring 30. This coiled spring is provided inside with a series 45 of links 31. The first one is pivoted by a vertical pin 32 to the stud 27. The rest are vertically pivoted to each other, except that two of them 33 and 34 are provided respectively with a dove-tail groove and a dove-tail projection 35 so that they are slidably keyed 50 together. One of the links, as for example, 34, is pivoted by a vertical pin 36 to a link 37 to which the other end of the spring 30 is connected by the pin 36. This link 37 is pivoted by a pin 39 to the arm 14 at a point 55 normally adjacent to the end 12 of the strut 11. It will be noted that all the pins 32, 36 and 37 are arranged vertically. Therefore, these links will hold up the spring throughout its length. The end of the link 37 is 60 cylindrical or semi-cylindrical preferably, and engages the inner curved surface of the end 12 which is of the same shape, and the spring forces the bumper arm 14 outwardly into that position normally. I have shown

these springs 30 as covered by a leather covering 40 which is secured to the springs near their ends by collars 41 to keep out dirt and moisture. The bumper is held up by the links which cannot swing downwardly. The struts 11 would also hold up the bumper 70 when in normal position.

Operation.

When the parts are placed in the position shown in full lines in Fig. 1, the springs 30 and the springs 23 will hold them in that position. If the bumper strikes a pedestrian or any other object at any point between the two pivots 39, the bumper will yield and the two bumper arms 14 will swing inwardly to the position shown in Fig. 2, if the person struck is in such position and the speed is sufficiently high to cause that operation. It will be seen that the springs 23 can yield as the block 20 moves backwardly to enable the arms 14 to assume the position shown. During the first part of the motion the ends of the bumper arms will move along in contact with the ends 12 of the struts 11, but soon they will leave contact with the same 80 and swing inwardly as indicated. The dotted lines in Fig. 1 show the device completely folded back with nothing between the arms.

If the pedestrian encountered strikes one 95 of the arms 14 at a point beyond the adjacent pivot pin 39 that arm will remain rigid on account of the support given it by the strut 11, and the construction of the block 12 and its connection with the two arms. Therefore, in this position the bumper will act like 100 any ordinary one-piece bumper.

It will be seen that the danger of serious accident to any person struck by the bumper is very greatly reduced, and that the danger of throwing him under the car is almost entirely eliminated. Catching him between the arms 14 as shown in Fig. 2 might bruise him a little in some cases, but it will not seriously injure him. In this way a great source of serious accidents is very materially reduced. It will be seen also that the device when in use presents substantially the appearance of an ordinary simple one-piece bumper, that there is very little mechanism connected with it, and that it is of such a 110 nature as not to get out of adjustment or wear out in operation.

Although I have illustrated and described only a single embodiment of my invention, I am aware of the fact that modifications can be made therein by any person skilled in the art without departing from the scope of the invention as expressed in the claims.

Therefore, I do not wish to be limited to all the details herein shown and described, but what I do claim is:—

1. In an automobile bumper, the combination of two opposite arms and a center

block, said arms being pivotally connected with the center block and capable of swinging inwardly at that point, and means for rigidly supporting said arms at points at a 5 distance from their ends.

2. In an automobile bumper, the combination with two pivoted arms of channel form pivotally connected near the center, of a pair of struts permanently and fixedly 10 mounted on the car having forward ends extending into and fitting within the arms to support them, and having sliding connection therewith.

3. In an automobile bumper, the combination of a pair of rigid struts secured to opposite sides of the car and projecting forwardly, a pair of bumper arms resting on the ends of said struts but not positively connected therewith, and means whereby 20 the inner ends of said arms can swing backwardly but the outer ends can not.

4. In an automobile bumper, the combination with a pair of struts rigidly mounted on the car and projecting forwardly therefrom, of a pair of bumper arms supported by the ends of said struts in such a way that the arms can move along the ends of the struts inwardly, and means on the arms for engaging the struts on their inner surfaces and preventing the arms from moving outwardly thereon.

5. In an automobile bumper, the combination of two opposite arms and a center block, said arms being pivotally connected with the center block and capable of swinging inwardly at that point, and means for rigidly supporting said arms at points adjacent to but at a distance from their ends, the center block extending beyond the adjacent ends of the bumper arms to prevent their swinging forwardly, whereby the ends of the arms beyond the said support will not yield backwardly upon hitting an obstruction.

6. In an automobile bumper, the combination with a pair of struts rigidly mounted on the car and projecting forwardly and outwardly therefrom, of a pair of bumper arms supported by the ends of said struts but not positively connected therewith, whereby the arms can move along the ends of the struts inwardly and be separated from them, means on the arms for engaging the struts on their inner surfaces and preventing the arms from moving outwardly thereon and means connected with said arms for preventing their sinking downwardly even when not supported by the struts.

7. In an automobile bumper, the combination with a pair of bumper arms, of means for supporting the ends of said arms, whereby the arms can move therealong inwardly, means on the arms for engaging the supporting means on their inner sur-

faces and preventing the arms from moving outwardly thereon, and a series of links pivotally connected together on vertical axes and capable of longitudinal and swinging motion about said axes but incapable of swinging downly and positively connected 65 with said arms for preventing their motion in a downward direction at all times.

8. In an automobile bumper, the combination with a pair of bumper arms, and means for movably supporting them, comprising a 70 series of links pivotally connected together on vertical axes and capable of longitudinal and swinging motion about said axes, positively connected with said arms for preventing their motion in a downward direction at all times, and a pair of heavy coiled springs connected with the frame of the car at one end and connected with said links for resisting motion of the arms backwardly.

9. In an automobile bumper, the combination with a pair of bumper arms means for movably supporting them, whereby the arms can move therealong inwardly, means on the arms for preventing the arms from moving outwardly, a series of links pivotally connected together on vertical axes and capable of swinging motion about said axes, connected with said arms for preventing their motion in a downward direction at all 80 times, a pair of heavy coiled spring connected with the frame of the car at one end and surrounding said links for resisting motion of the arms backwardly, and a covering of flexible material over the springs for preventing access of dirt and moisture 85 thereto.

10. In an automobile bumper, the combination of a pair of bumper arms located normally in alignment and pivotally mounted at points at a distance from their ends, with 90 a block located between the adjacent ends of said arms and having a loose permanent pivotal connection with both of said arms and provided with means for preventing the arms from moving forwardly about 95 their pivots from normal position.

11. In an automobile bumper, the combination of a pair of bumper arms located normally in alignment and pivotally mounted at points adjacent to but at a distance 105 from their outer ends, with a block fitting between the ends of said arms and having a loose permanent pivotal connection with both of said arms, said connections comprising a pair of pivot members pivoted to 110 said arms near the inner ends thereof and yielding means for connecting said pivot members with the center block.

12. In an automobile bumper, the combination of a pair of pivoted arms normally 115 in alignment with each other, a center block filling the space between them, said block having opposite projections extending along 120

the inner surfaces of said arms, a pair of pivot members pivoted to said arms near their inner ends and extending inwardly, a pair of bolts extending through said arms and normally located in alignment transverse to the longitudinal dimension of the car and having their heads located beyond

the opposite ends of said block and connected therewith, and springs between the opposite ends of said center block and the adjacent sides of the pivot members.

In testimony whereof I have hereunto affixed my signature.

THOMAS D. TERLIZZI.
